UNITED STATES PATENT OFFICE

164,401

ALPHABET FOR FORMING MONOGRAMS OR THE LIKE

Marvin Caplan, Baltimore, Md., assignor to Oscar Caplan & Sons, Inc., Baltimore, Md., a corporation of Maryland

Application November 23, 1949, Serial No. 6,212

Term of patent 14 years

(Cl. D64—12)

To all whom it may concern:

Be it known that I, Marvin Caplan, a citizen of the United States, residing at the city of Baltimore, State of Maryland, have invented a new, original, and ornamental Design for an Alphabet for Forming Monograms or the like, of which the following is a specification, reference being had to the accompanying drawings, forming part thereof.

Figure 1 illustrates face views of the alphabet for forming monograms or the like, showing my new design.

Figure 2 is a perspective view of the letter "M" which shows a typical third dimension of all of the letters.

I claim:
The ornamental design for an alphabet for forming monograms or the like, as shown and described.

MARVIN CAPLAN.
